UNITED STATES PATENT OFFICE.

GEORGE M. LANE, OF ASBURY PARK, NEW JERSEY.

SPRING-HINGE.

SPECIFICATION forming part of Letters Patent No. 298,480, dated May 13, 1884.

Application filed January 12, 1884. (Model.)

To all whom it may concern:

Be it known that I, GEORGE M. LANE, a citizen of the United States, residing at Asbury Park, in the county of Monmouth and State of New Jersey, have invented certain new and useful Improvements in Spring-Hinges; and I do declare that the following is a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in spring-hinges; and it consists in the novel construction, combination, and arrangement of the several parts, as will be hereinafter fully described and claimed.

20 In the drawings, Figure 1 is a front view of my hinge. Fig. 2 is a detail view of the pintle and spring. Fig. 3 is a detail of the ratchet-ring. Fig. 4 is a detail of the spring-cap. Fig. 5 is a detail of the pawl-plate; Fig. 6, a 25 detail view of the upper knuckle inserted; Fig. 7, a detail view of the middle knuckle; Fig. 8, a detail view of the lower knuckle, all of which will be described.

I have shown my invention as applied to a 30 surface-hinge. It will be understood, however, that it may be made a mortise or double-acting hinge without any departure from the principles of my invention.

The plate A is provided with the middle 35 knuckle, A'. This knuckle is provided in its upper end with two broad shallow slots, A², arranged diametrically opposite each other, as most clearly shown in Fig. 7. A narrow slot, A³, is formed downward from the center of 40 each slot A², for the purpose presently described.

The plate B is provided with the upper and lower knuckles, C D. The knuckle C is provided in its lower side with slots C', arranged 45 diametrically opposite each other. The outer end of these slots is of a width equal that of the slots A², and its sides are beveled inward toward the base, as shown. The lower knuckle, D, has its lower end closed, and is provided in 50 its upper end with slots D', from the lower end of which I form laterally a wing, D².

These wings are extended in the same circumferential direction from both the slots.

The ratchet-ring E is formed with the central opening, E', and has notches E² on its periphery. These notches are beveled on one side and straight on the other. A cross-bar, F, extends across the opening E'. I prefer to use this cross-bar in order to better support the end of the spring, as presently described; 60 but good results will be had if, instead thereof, short radial projections F' are formed on the inner walls of the opening E', as shown in the lower view in Fig. 3.

The pawl-plate G is made of a size to fit in 65 the knuckle D, and is formed with a central pintle-opening, G'. Pawls H are secured or formed on the periphery of this plate and extend upward therefrom. These pawls are movable vertically in the slots D, and are provided 70 on one side, near their lower ends, with lateral projections H', arranged to turn into the wings D² and hold the pawl-plate down against the tension of spring I when so desired. This spring I is placed in the knuckle D, and bears 75 against the base thereof and the under side of pawl-plate G, holding the same normally up in the position shown in Fig. 1.

The spring-cap J is formed with a central pintle-opening, J', and is made of an external 80 diameter fitted to the internal diameter of knuckle A'. It is placed in the upper end of this knuckle, and is provided with radial lugs K, fitted to the slots A³ therein. On the upper side of the spring-cap I form sliding surfaces 85 K', which extend radially over and above the lugs K. These surfaces K' are made of a size to fit the slots C' of knuckle C, and are beveled on their opposite ends correspondingly to the bevel of the walls of said slot C'. A slot, K², 90 is formed in the lower end of the spring-cap and through one side of one of the lugs K, as most clearly shown in Fig. 4.

The pintle L has its lower end slotted or bifurcated, forming legs L', and is provided at 95 its upper end with an opening, L², to receive a pin whereby the pintle may be rotated. Where desired, the pintle may be formed with an angular head to receive a wrench. The tension-spring M is coiled around pintle L, and 100 its lower end, M', is passed between the legs L', as clearly shown in Fig. 2.

In putting my hinge together, the spring I is placed in knuckle D, the pawl-plate is pressed down in said knuckle against the pawl-spring, so as to bring its portions H' opposite wings D² of the slots D. The plate G is then turned and extensions H' catch in slots D², and the pawls are held from any upward movement. The upper ends of the pawls are now approximately flush with the upper end of the lower knuckle. The tension-spring is placed in the knuckle A', and the ratchet-ring and spring-cap placed against respectively its lower and upper ends. The lower end of the spring bears against and in line with cross-bar F of the ratchet-ring, and its upper end, M², is extended through slots K² and out through A³, as clearly shown. The ratchet-ring is now pressed firmly against the lower side of the knuckle A', and the spring-cap is forced down at its upper end until the surfaces K' rest within slots A². These parts are then slipped between the knuckles C D, and the pintle is inserted from above through knuckle C and spring M, and its legs L' pass down on opposite sides of the end M' of spring M and the cross-bar of the pawl-plate. The pawl-plate is now released and its spring forces it into engagement with the ratchets of ring E. By turning the pintle the hinge-spring may be wound to any suitable desired tension. As it is thus wound the ratchet-plate is also turned, and is held at any desired point by the pawl, as will be readily understood. In Fig. 1 the hinge is represented as closed. To open same the longitudinal force of the hinge-spring holding-cap J in slot C' must be overcome. By this means the door is held closed against the wind, as will be understood. When the hinge is open, the longitudinal tension of the spring will again force the spring-cap lugs into the slots C' and hold the door open.

Having thus described my invention, what I claim, and desire to secure by Letters Patent, is—

1. The combination of the lower knuckle, the 45 knuckle C, provided with slots C', the knuckle A', arranged between said knuckles, and the spring-cap arranged in knuckle A' and interposed between the spring and the knuckle C, and provided with sliding surfaces adapted to 50 enter the slots C' when the spring is at rest, whereby the longitudinal expansion of the spring is utilized at such times to hold the door against the force of the wind, substantially as set forth. 55

2. In a spring-hinge, the combination of the knuckle D, having slots D', the spring I, arranged in said knuckle, the plate G, placed on said spring and provided with pawls H, the ratchet-ring having a suitable cross-bar or 60 transverse projections, and the hinge-spring and bifurcated pintle, all arranged and operating substantially as set forth.

3. In a spring-hinge, the combination, with the knuckle A', having slots A² A³, of the spring- 65 cap J, having sliding surfaces K' and slot K², and the hinge-spring and pintle, substantially as and for the purposes specified.

4. The combination of the knuckle D, provided with slots D', having lateral wings D², 70 the pawl-spring, the pawl-plate provided with pawls having lateral extensions H', and the ratchet-ring, pintle, and hinge-spring, substantially as and for the purposes specified.

In testimony whereof I affix my signature in presence of two witnesses.

GEORGE M. LANE.
